UNITED STATES PATENT OFFICE.

STEPHEN W. CORIASCO, OF CLINTON, MASSACHUSETTS.

MACHINE FOR MAKING WIRE ROPE.

SPECIFICATION forming part of Letters Patent No. 727,751, dated May 12, 1903.

Application filed November 21, 1902. Serial No. 132,284. (No model.)

To all whom it may concern:

Be it known that I, STEPHEN W. CORIASCO, a citizen of the United States, residing at Clinton, in the county of Worcester and State of Massachusetts, have invented a new and useful Machine for Making and Straightening Wire Rope, of which the following is a specification.

This invention relates to that class of machines which are employed for wrapping a covering of wire around a central cord or strand or which may be employed for forming a hollow wire cable.

The objects of this invention are to provide a strong, simple, and efficient machine of this class in which the spinning or twisting head will be so constructed as to handle a comparatively large number of strands or wires, to provide special gearing for turning the supply-reels, so that the wires will be associated smoothly together with a slight twist in the completed product, and to provide an arrangement of coaxing-pulleys for straightening the completed product.

To these ends this invention consists of the parts and combinations of parts, as hereinafter described, and more particularly pointed out in the claims at the end of this specification.

In the accompanying two sheets of drawings, Figure 1 is a side view of a machine for making and straightening wire rope constructed according to this invention. Fig. 2 is a diagrammatic view illustrating the operation of the coaxing-pulleys for straightening the completed rope. Fig. 3 is a plan view of the machine, partly in section. Fig. 4 is a detail view of the gearing carried by the spinning-head. Fig. 5 is a diagrammatic view illustrating the operation of the spinning-head, and Figs. 6 and 7 are fragmentary views of the completed product.

In a machine for making and straightening wire rope constructed according to this invention the wires are drawn from reels or spools mounted in a spinning-head. The wires are wrapped spirally around a central wire or may be associated to form a hollow cable. In order to prevent too much twist 45 from being imparted to the individual wires when they are laid spirally together, a sun-and-planet gearing is employed for turning

the reels or spools, which are carried in the spinning or twisting head. One especial object of the present invention is to construct 55 the gearing for this purpose in a compact and simple manner, so that a comparatively large number of strands may be associated together. To accomplish this purpose in a machine constructed according to this invention, a part 60 only of the stub-shafts which carry the reels or supply-spools are turned by intermediates from a stationary central or sun gear, while the remainder of the stub-shafts are driven by small intermediates from the stub-shafts 65 which are primarily driven.

When the machine is to be used for wrapping a covering around a central core, the central core or strand is drawn in through the hollow shaft of the spinning-head. If desired, however, a stationary former or mandrel can be inserted through the hollow shaft of the spinning-head, so that the wires will be wrapped thereon and then drawn off to form a hollow cable. The completed rope is 75 carried from a grooved pulley down under tapered coaxing-pulleys, which are preferably driven at higher speeds than the rate at which the rope is produced. The completed rope is 80 wound onto a reel or spool, and as the rope passing under the coaxing-pulleys will tend to run toward the larger diameter of such tapered coaxing-pulleys this action will serve to automatically straighten or stretch the rope as it is produced.

Referring to the accompanying drawings for a detail description of a machine for making and straightening wire rope constructed according to this invention, F designates the framework of the machine. Journaled in 85 boxes at the side of the frame F is a main driving-shaft 10. Secured on one end of the driving-shaft 10 is a cone-pulley 11, running on which is a driving-belt 12. Removably secured on the other end of the driving-shaft 90 10 is a pinion 13, which meshes with an intermediate gear 15, adjustably fastened upon a sweep or arm 14. The intermediate gear 15 meshes with and drives a gear 16, removably secured on the end of the hollow spinning-head shaft 19. By replacing the gears 13 and 16 with gears of different sizes the spinning-head may be driven at proper speeds, according to the gage of the wire and character of

product being produced. The shaft 19 is journaled in a bearing 17, and keyed to or otherwise fastened to the bearing 17 is a stationary central or sun gear 18. The spinning-head carried by the shaft 19 preferably comprises two parallel plates, and journaled in the parallel plates are stub-shafts 20, carrying reel-frames 21, removably journaled in which are the supply spools or reels 22.

10 A machine constructed according to my invention is preferably adapted to handle a considerably larger number of strands than has heretofore been the practice in machines of this class. The machine herein illustrated 15 is adapted to handle twelve separate strands or wires.

The arrangement of gearing for driving the separate stub-shafts in the spinning-head is most clearly illustrated in Fig. 4. As shown 20 in this figure, the spinning-head is provided with four intermediate gears 23, which mesh with and drive gears 25 on four of the stub-shafts 20. Meshing with the gears 25 are intermediates 26, which drive gears 46 of the 25 remainder of the stub-shafts 20. The gears 25 and 46 are preferably slightly larger than the central stationary gear 18. By means of this construction, as illustrated most clearly in Fig. 5, each of the wires or strands W will 30 be given a partial twist when drawn from its reel or spool. The greater part of this twist, however, will be taken out when the wires are associated together. When the machine is using the harder grades of wires, however, 35 it is desirable that a slight twist should be left in each of the separate strands, as I have found in practice that this will cause the wires to lie more compactly together than when laid with no twist at all in the completed 40 product, and this result is accomplished by the slight difference in diameter between the external gears 25 and 46 and the central gear 18.

As shown most clearly in Fig. 1, the 45 low shaft 19 is provided at its forward end with a perforated disk 27, which runs in a half-bearing 28. From the perforated disk 27 the wires pass through grooves in the conical head 29, and the completed rope is drawn 50 through a die 30 and around a grooved pulley 31. From the grooved pulley 31 the rope passes under tapered coaxing-pulleys 32 and 33 to a reel 34. The coaxing-pulleys 32 and 33 are preferably driven at increased speeds. 55 As illustrated, the gearing for this purpose comprises a worm 35, secured on the main shaft 10, which meshes with and drives a worm-wheel turning with the first coaxing-pulley 32. Secured on the shaft of the coaxing-pulley 32 is a sprocket-wheel, which, through a sprocket-chain 36, drives the second coaxing-pulley 33. The coaxing-pulley 33 is connected by a belt 37 to turn the reel 34, upon which the completed rope is wound. 65 A belt-tightener 38 is also preferably employed for maintaining a proper tension of the belt 37. As the rope passes beneath the

coaxing-pulleys 32 and 33, as illustrated most clearly in Fig. 2, it will tend to run up onto the larger diameters of said coaxing-pulleys, 70 and this in practice I have found will impart the required tension or pull to the rope, which is necessary for straightening and perfecting the same.

As illustrated most clearly in Fig. 3, the 75 shaft of the second coaxing-pulley 33 may be provided with a worm-wheel 39, which meshes with and drives a graduating-disk 40 for measuring the length of rope produced.

I am aware that numerous changes may be 80 made in practicing my invention by those who are skilled in the art without departing from the scope thereof as expressed in the claims. I do not wish, therefore, to be limited to the constructions I have herein shown 85 and described; but

What I do claim, and desire to secure by Letters Patent of the United States, is—

1. In a machine for making wire rope, the combination of a winding-head, supply-spool 90 shafts journaled therein, intermediate gears connecting the shafts of the supply-spools, and a sun-and-planet gearing for driving a portion of the shafts.

2. In a machine for making wire rope, the 95 combination of a winding-head, supply-spool shafts journaled in the winding-head, a sun-and-planet gearing for turning part of said shafts, and intermediate gears connecting the primarily-driven supply-spool shafts with 100 the adjacent supply-spool shafts.

3. In a machine for making wire rope, the combination of a winding-head, a set of primarily-driven supply-spool shafts journaled in the winding-head, a sun-and-planet gearing turning the supply-spool shafts, and additional winding-spool shafts interposed 105 between the primarily-driven winding-spool shafts and connected by intermediate gears therewith. 110

4. In a machine for making wire rope, the combination of a winding-head, supply-spool shafts journaled near the periphery of the winding-head, intermediate gears connecting said shafts, a central stationary gear, and intermediate gears connecting the central gear with a part of the winding-spool shafts. 115

5. In a machine for making wire rope, the combination of a hollow shaft, a winding-head carried thereby, and comprising parallel disks 120 or plates, supply-spool shafts journaled near the periphery of the plates, supply-spool frames carried by the shafts with supply-spools removably journaled in the frames with their axes parallel with the plane of the 125 rotation of the winding-head, intermediate gears connecting the shafts, a central stationary gear, and intermediate gears connecting the central stationary gear with a part of the shafts, said gears being arranged between 130 the plates or disks of the winding-head.

6. In a machine for making wire rope, the combination of a hollow shaft, a winding-head mounted thereon, supply-spool shafts jour-

naled in the winding-head, sun-and-planet gearing for turning the supply-spool shafts, a driving-shaft, and a change-speed gearing connecting the driving-shaft with the hollow shaft.

7. In a machine for making wire rope, the combination of a hollow shaft, a winding-head carried thereby, supply-spool shafts journaled in the winding-head, a sun-and-planet gearing for turning the supply-spool shafts, a driving-shaft, and a change-speed gearing connecting the driving-shaft with the hollow shaft, comprising replaceable gears on the driving-shaft and hollow shaft respectively, and a sweep carrying an intermediate gear for connecting the replaceable gears.

8. In an apparatus of the class described, the combination of the die in which individual strands are associated to form a wire rope, a

grooved pulley for holding the wire rope in line with its die, a winding-reel, tapering coaxing-pulleys around which the rope passes between the die and winding-reel, and driving connections for turning the tapering coaxing-pulleys at higher speed than the travel of the wire rope, to exert a coaxing or combining action thereon, said parts being arranged so that the tendency of the rope to run to the larger diameter of the pulleys will stretch and straighten the same.

In testimony whereof I have hereunto set my hand in the presence of two subscribing witnesses.
